UNITED STATES PATENT OFFICE

141,598

DESIGN FOR A CHILD'S PLATE

William Abrams, Chicago, Ill., assignor to Isidore Feldman, Chicago, Ill.

Application September 23, 1944, Serial No. 115,415

Term of patent 3½ years

(Cl. D44—15)

To all whom it may concern:

Be it known that I, William Abrams, a citizen of the United States, residing at Chicago, in the county of Cook and State of Illinois, have invented a new, original, and ornamental Design for Child's Plate, of which the following is a specification, reference being had to the accompanying drawings, forming a part thereof.

In the drawings:

Fig. 1 is a front perspective view of a child's plate showing my new design,

Fig. 2 is a top plan view thereof, and

Fig. 3 is a side elevational view thereof.

I claim:

The ornamental design for a child's plate, as shown.

WILLIAM ABRAMS.
